UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed May 26, 1927. Serial No. 194,279.

This invention relates to typographical machines, such as linotype machines of the general organization represented in U. S. Letters Patent to O. Mergenthaler, No. 436,532, wherein circulating matrices are released from a channeled magazine in the order in which they are to appear in print and then assembled in line, the composed line transferred to the face of a mold, the mold filled with molten metal to form a slug or linotype against the matrices which produce the type characters thereon, and the matrices thereafter distributed according to character and returned through a channeled magazine entrance to the magazine from which they started.

In these machines, the magazine entrance is usually provided with a series of partitions which divide it into matrix channels and which are formed at their lower ends with bent-over flanges arranged to guide the matrices by their projecting ears as they pass to the magazine. In some instances, as when the entrance channels are extremely wide, these flanges are formed on auxiliary guiding elements or leaf sections which are fastened to the partitions and disposed at an inclination thereto so as to contract the channels toward their delivery ends,—see Kennedy Patent No. 1,367,606. While such arrangement enables the entrance to handle matrices of varying thicknesses in many different fonts, its capacity is nevertheless limited. That is to say, the range in thickness of certain matrices of corresponding character in many fonts, particularly those used in setting advertising and display matter, is so great that some of the largest and smallest faces are excluded from use in the regular machines. While the present invention is intended primarily to obviate this difficulty by making one or more of the aforesaid leaf sections adjustable to vary the widths of the respective channels and thus adapt the entrance to handle the matrices of all available display fonts, it is directed more specifically to certain improvements in the means employed for effecting such adjustments. In the preferred embodiment illustrated, the adjustable leaf sections are hinged at their upper ends and connected at relatively different points below their respective hinges to a movable strip or plate which is operated by a stepped

cam rotatably mounted on the entrance supporting frame.

In the accompanying drawings, the invention is shown merely in preferred form and by way of example and as applied to a particular kind of linotype machine, but obviously many changes and variations may be made therein and its application be extended to other types of machines without departure from its spirit. It should, therefore, be understood that the invention is not limited to any specific form or embodiment except in so far as such limitations are specified in the claims.

Referring to the drawings:

Fig. 1 is a side elevation of a magazine entrance partly broken away and equipped with the present improvements;

Fig. 2 is a sectional plan view taken on the line 2—2 of Fig. 1; and

Fig. 3 is a transverse section taken on the line 3—3 of Fig. 1.

The magazine entrance A, which is employed in machines of the class described to conduct the matrices from the distributor (not shown) to the magazine B, is divided into channels by the partitions A¹ which bear a fixed relation to one another and are spaced different distances apart to better accommodate a display font of maximum thickness. In adapting the channels to handle the matrices of thinner fonts, however, the partitions A¹ are usually provided with inclined guiding elements, or leaf sections A², which are connected at their upper ends to the partitions A¹ and are formed (although not necessarily so) at their lower ends with bent-over flanges a for guiding the matrices by their projecting ears. Spacing blocks a¹ of varying thicknesses, while not essential, are preferably interposed between the lower ends of the leaf sections A² and the adjoining partitions to maintain the former at the inclination desired. The widths of the channels are thus contracted in advance of the flanges a so that the thinner matrices in descending through the relatively wide channels will be straightened up and caused to enter the magazine in the proper position. There are a number of characters, however, whose range in thickness in the different display fonts is so great that, if the leaf sections A² be spaced far enough from the opposing partitions to al-

low the thickest matrices to pass freely therebetween, the thinner matrices of the corresponding character in passing through the same channels would be allowed to tilt 5 at such an angle that their projecting ears would fail to properly engage the flanges a and likely become lodged beneath them so as to cause a piling up of succeeding matrices.

- 10 To overcome the above difficulty, certain of the leaf sections, instead of being rigidly connected to the partitions, are made adjustable in relation thereto so as to vary the widths of the respective channels according 15 to the thickness of the corresponding characters being used. These particular leaf sections A^3 are hingedly mounted at their upper ends on trunnions a^2 which are journaled in small bracket members A^4 riveted 20 to the partitions A^1 . The bracket members A^4 (see Figs. 1 and 2) are formed with beveled or inclined portions a^3 which fit against the side faces of the partitions and present smooth guiding surfaces to the descending 25 matrices. The adjustments of the leaf sections A^3 are accomplished by means of a longitudinal plate or strip C which is slidably mounted for endwise movement in the entrance supporting frame A^5 and arranged 30 below the lower end portions of the partitions A^1 , forming in effect a section of the bottom plate of the entrance. A pin and slot connection C^1 , located at opposite ends of the strip, restrains it against dis- 35 placement and permits the endwise movement desired. So far as described, the parts are or may be the same as those embodied in the pending application of G. A. Doxey, Serial No. 171,927, and in themselves constitute 40 no part of the present invention.

Since the relative thickness of the various matrix characters is approximately the same in the different display fonts, it is very important that the leaf sections A^3 be capable 45 of a corresponding relative adjustment in order to vary the widths of the respective entrance channels according to the size of the particular font selected. In other words, all of the said leaf sections should have the same rate of adjustment 50 but the extent of their adjustment individually should vary according to the widths of the respective channels. For example, if one channel were half the width of another, the extent of adjustment of its respective leaf section should, generally speaking, be half of that of the leaf section for the wider channel. The present invention, therefore, contemplates means whereby 55 such adjustments may be accurately effected and consistently carried out for all of the leaf sections A^3 in handling display fonts of the different sizes. To this end, the leaf sections A^3 are connected to the plate 60 C at different predetermined distances be-

low their respective pivotal axes a^2 so that all of them will be adjusted in the manner required by each operation of said strip. It is obvious that the leaf sections might be connected to the plate C in different ways, 70 but in the present embodiment there are employed pins c which protrude above the top of the plate C between the partitions and the leaf sections and are arranged to engage the leaf sections at the desired point below their respective axes. Since the leaf sections A^3 are alike in form and all of them are hinged to the partitions A^1 at the same distance above the delivery end of the entrance, the extent of their adjustment may 75 be readily determined by locating the pins in the proper relation to their respective hinges. It is, of course, conceivable that, as an alternative, the pins could be arranged in alignment and the hinges located at different 80 distances above the pins, but this would involve a separate die for each leaf section and be otherwise objectionable.

In order to effect the adjustment of the leaf sections with the desired degree of accuracy, the plate C is operated by means of a rotary cam element D arranged adjacent one end thereof and mounted to turn upon a suitable bearing screw D^1 threaded into the entrance frame A^5 —see Fig. 3. The 90 inner side of the cam element D is formed with a series of stepped banking surfaces d and intervening cam surfaces d^1 which engage a hardened stud C^2 supported in a small bracket C^3 secured to the plate C . A 95 light pull spring C^4 , anchored to the entrance frame and connected to the plate C , tends constantly to hold the latter against one or another of the banking surfaces d . The cam element D , in the present instance, 100 is rotated by hand and, to facilitate the operation, is further formed with a peripheral knurled surface D^2 . Suitable scale markings C^5 , such as those shown in Fig. 2, are also provided to assist the operator in 105 adjusting the leaf sections for any selected font ranging from $5\frac{1}{2}$ to 36 pt. These markings are formed on the plate C and are adapted to register with a corresponding mark on the bottom plate of the entrance A 110 as the cam element is rotated.

According to the foregoing arrangement, when it is desired to adjust the leaf sections A^3 to conform to a new matrix font, the cam element is rotated in one direction or the other to bring a selected banking surface opposite the stud C^2 . If a thinner font is to be substituted for the one being used, the cam element is turned in an anti-clockwise direction, and as the stud C^2 rides over the bevels 120 or cam surfaces d^1 , the spring C^4 is allowed to draw the plate C to the right. The pins c will thus be caused to swing the leaf sections in the same direction to decrease the widths of the respective channels to the ex- 125 130

tent determined by the banking surface selected and the location of the corresponding pins *c*. In changing from a thin to a thicker font, the cam element is turned in the opposite direction so as to force the plate *C* to the left against the tension of the spring *C*'; and while the pins *c* by such operation do not actually move the freely hinged leaf sections to expand the channels, they are intended to support them at the proper inclination, it being understood that the first matrix of the newly selected font in passing through the channels will swing the leaf sections to their normal adjusted positions against the pins. If, however, it should be found desirable to swing the leaf sections positively in both directions to their different adjusted positions, the pins *c* could readily be substituted by ears formed on the bottom edge of the respective leaf sections and permanently engaging corresponding apertures in the plate *C*, but the results of course would be precisely the same. Due to their location between the partitions and the hinged leaf sections, the adjusting pins *c* never lie in the path of travel of the matrices, which thus have a free passage through the magazine entrance in any adjusted position of the leaf sections. Many other changes and variations will readily suggest themselves to those skilled in the art and still be comprised within the scope of the invention.

Having thus described my invention, its construction and mode of operation, what I claim and desire to secure by Letters Patent of the United States is as follows:

1. In a typographical distributing machine, the combination of a magazine entrance provided with a plurality of partitions dividing it into channels, with guiding elements adjustable relatively to the partitions, and operating means connected to said elements and adapted at each operation to adjust all of them simultaneously but to different relative extents, for the purpose described.

2. In a typographical distributing machine, the combination of a magazine entrance provided with a plurality of partitions dividing it into channels of different widths, with adjustable leaf sections attached at their upper ends to the partitions, and a movable strip connected to said leaf sections and adapted at each operation to adjust all of them simultaneously but to different relative extents according to the widths of the respective channels.

3. In a typographical distributing machine, the combination of a magazine entrance provided with a plurality of partitions dividing it into channels, with leaf sections mounted on hinges within the channels, and means engaging the leaf sections at different points below their respective

hinges for adjusting them to different relative extents, for the purpose described.

4. In a typographical distributing machine, the combination of a magazine entrance provided with a plurality of partitions dividing it into channels of different widths, with leaf sections hinged to the partitions on a common line, and means engaging the leaf sections at different points below their respective hinges for adjusting them to different relative extents according to the widths of said channels.

5. In a typographical distributing machine, the combination of a magazine entrance provided with a plurality of partitions dividing it into channels of different widths, with leaf sections hinged to the partitions on a common line, and unitary means engaging the leaf sections at relatively different points below their respective hinges for adjusting them simultaneously but to different relative extents according to the widths of said channels.

6. In a typographical distributing machine, the combination of a magazine entrance provided with a plurality of partitions dividing it into channels, with adjustable leaf sections attached at their upper ends to the partitions a given distance from the delivery end of the entrance, a movable strip engaging the respective leaf sections at relatively different points below their upper ends and operable to adjust said sections to different relative extents within the channels, and means for operating the strip.

7. In a typographical distributing machine, the combination of a magazine entrance provided with a plurality of partitions dividing it into channels, with leaf sections mounted on hinges within the channels, and means for adjusting the leaf sections relatively to the partitions to vary the widths of the channels, said means comprising a movable strip provided with pins arranged to engage the leaf sections at relatively different points below their respective hinges.

8. In a typographical distributing machine, the combination of a magazine entrance provided with a plurality of partitions dividing it into channels, with leaf sections fixed to certain of the partitions and formed with bent-over flanges for guiding the matrices by their projecting ears, leaf sections hinged to the other partitions and formed without such flanges, and operating means connected with the hinged leaf sections so that all of them will be adjusted simultaneously to different relative extents across said channels at each operation of said means.

9. In a typographical distributing machine, the combination of a magazine entrance provided with a plurality of parti-

tions dividing it into channels of different widths, with leaf sections fixed to certain of the partitions and formed with bent-over flanges for guiding the matrices by their projecting ears, leaf sections hinged to other partitions and formed without such flanges, and means engaging the said hinged leaf sections at different points below their respective hinges for adjusting them to different relative extents according to the widths of the respective channels.

10. In a typographical distributing machine, the combination of a magazine entrance provided with a plurality of partitions dividing it into channels, with leaf sections hinged to the partitions, a mov-

able strip engaging the leaf sections and operable at will to adjust them relatively to the partitions, and means for indicating such adjustments. 20

11. A combination as in claim 7, characterized by the fact that the pins therein referred to are located between the leaf sections and the partitions to which said sections are hinged. 25

12. A combination as in claim 7, characterized by the fact that the leaf sections therein referred to are freely hinged to their respective partitions.

In testimony whereof, I have affixed my 30 signature hereto.

ALFRED W. F. GUEST.
